UNITED STATES PATENT OFFICE

2,494,511

BASE BAG WITH COVER

Joseph Josselson, Carmody Hills, Md.

Application August 3, 1946, Serial No. 688,301

4 Claims. (Cl. 273—25)

1

This invention relates to improvements in base bags with covers for use on a baseball diamond.

An object of the invention is to provide an improved base bag having a removable wear cover for the top and sides thereof which will take most of the wear from the players' cleats, thereby providing a much greater length of time the base bag will be serviceable before the same has to be replaced.

Another object of the invention is to provide an improved base bag and a removable protecting cover therefor, said cover being made with wear resisting cross stitched reinforcing welts over its upper surface and integrally formed depending sides adapted to be placed in position over a base bag and to be fastened thereto by means of spaced snap fasteners disposed on the several sides of said bag and cover.

A further object of the invention is to provide an improved base bag with crossed reinforcing and base positioning straps, and a detachable wear cover for said bag having spaced fastening snaps on its four sides adapted to hold said cover on the bag and to extend at the opposite sides of the strap buckles to hold the same in position.

Another object of the invention is to provide a reinforced wear resisting cover for base bags which will protect base bags from the hard usage given them by the cleats on the baseball players' shoes, said covers being considerably less expensive to replace than to replace the base bags.

Another object of the invention is to provide an improved base bag and detachable protecting cover therefor which will be highly efficient in use, and relatively inexpensive to manufacture and produce.

Other objects will appear as the description proceeds.

In the accompanying drawings which form a part of this application,

Figure 1 is a perspective view of a base bag with the improved protecting cover secured thereon;

Figure 2 is an exploded view of the base bag with the improved protecting cover removed therefrom;

Figure 3 is a top plan view of the improved base bag protecting cover;

Figure 4 is a bottom plan view of the improved base bag protecting cover;

Figure 5 is a partial sectional view taken on the line 5—5 of Figure 3;

Figure 6 is a side elevation of the base bag 55 thereon.

2

being partly broken away and in section to show the construction thereof, and

Figure 7 is a bottom plan view of the improved base bag.

Like characters of reference are used throughout the following specification and the accompanying drawings to designate corresponding parts.

In carrying out the invention, there is provided an improved base bag generally designated by the reference numeral 1, the same being substantially square in shape and provided with a double wall of canvas or other heavy fabric 2 and 3.

10 The base bag is preferably filled with layers of cotton 4, or with any other desired material. The upper surface of the base bag 1 is stitched at 5 to reinforce the same and the slotted leather reinforcing tabs 6, 7, 8 and 9 are sewed to the upper side edges of bag, said slots 10 providing means whereby the reinforcing and base bag positioning straps 11 and 12 may be inserted and crossed over the top of the bag between the layers of fabric 2 and 3. The straps will completely encircle the bag 1 and will be crossed on the outside thereof at the bottom of the bag, whereby means will be provided for securing the base bag in proper position upon a baseball diamond. The fastening

20 buckles 13 and 14 for the straps 11 and 12 will be disposed on the side edges of the bag 1 to lie between the spaced male portions 15 and 16 of the snap fasteners, reinforcing stitching 17 being run about the fasteners to keep the same in position.

25 Another object of the invention is to provide a reinforced wear resisting cover for base bags which will protect base bags from the hard usage given them by the cleats on the baseball players' shoes, said covers being considerably less expensive to replace than to replace the base bags.

Another object of the invention is to provide an improved base bag and detachable protecting cover therefor which will be highly efficient in use, and relatively inexpensive to manufacture and produce.

Other objects will appear as the description proceeds.

In the accompanying drawings which form a part of this application,

Figure 1 is a perspective view of a base bag with the improved protecting cover secured thereon;

Figure 2 is an exploded view of the base bag with the improved protecting cover removed therefrom;

Figure 3 is a top plan view of the improved base bag protecting cover;

After continued use, the removable covers may become cut and require replacement, and by using these replaceable wear covers, the base bags may be used with a number of the protecting covers before they are rendered unusable. Since the cost of the protecting covers is relatively small in comparison with the cost of the base bags, a decided saving in the cost of the base bags used during a playing season will be effected.

From the foregoing description, it will be apparent that there has been provided a highly efficient and useful base bag and replaceable protecting cover therefor which will entail a decided savings in expense for base bag equipment over the base bags now on the market.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A base bag comprising a case having side walls, a top and a bottom each of which being of a double thickness of material, the said top having slots in the outer thickness of material adjacent the top edges of the case, straps extending through opposed slots and crossing between the thicknesses of material in the top of the case, said straps crossing on the outer thickness of said bottom.

2. A base bag comprising a case having side

walls, a top and a bottom each of which being of a double thickness of material, the said top having slots in the outer thickness of material adjacent the top edges of the case, straps extending through opposed slots and crossing between the thicknesses of material in the top of the case, said straps crossing on the outer thickness of said bottom, and fastening means secured to said sides for attachment of a replaceable cover.

3. A base bag comprising a case having side walls, a top and a bottom each of which being of a double thickness of material, the said top having slots in the outer thickness of material adjacent the top edges of the case, straps extending through opposed slots and crossing between the thicknesses of material in the top of the case, said straps crossing on the outer thickness of said bottom, and slotted wear tabs adjacent said slots secured to the outer thickness of said top.

4. The combination of claim 2, and a cover having sides, a top portion and an open bottom, and means attached to said sides spaced from the edges thereof for cooperation with said fastening means to attach the cover to the case.

JOSEPH JOSSELSON.
